POLISHING APPARATUS

Alfred E. Hamilton, Pittsburgh, Pa.

Application November 14, 1936, Serial No. 110,863

8 Claims. (Cl. 51—84)

My invention relates to polishing or abrading machines and is hereinafter described as employed in the polishing of knife blades or the like, although it will be apparent that it may be employed in the polishing and finishing of other articles.

One object of my invention is to provide means for effecting a cross-polishing of the blanks simultaneously with a polishing operation, in directions length-wise of the blanks, and wherein the efficiency of the cross-polishing operation will be the same regardless of the length of feed stroke employed in directions length-wise of the blanks.

Another object of my invention is to provide a mechanism for moving the blanks in directions longitudinally of the rolls during advancing and retracting movements thereof between the rolls, with a vibratile-reciprocatory motion derived from a hypocyclic crank movement.

Another object of my invention is to provide a simplified automatic stopping mechanism that is readily adjustable to permit the desired number of abrading strokes or the proper number of polishing strokes, whereby the danger of under-working or over-working of the blanks is eliminated.

A further object of my invention is to provide a machine of such form that the various working parts can readily and easily be adjusted; wherein the parts are fully protected against entry of abrasive and other foreign material, and which shall be capable of efficient and continuous operation.

In the accompanying drawings, Figure 1 is a front view of the machine; Fig. 2 is a plan view thereof, partly in section; Fig. 3 is a side view thereof; Fig. 4 is a view on an enlarged scale taken on the line IV—IV of Fig. 1; Fig. 5 is an enlarged view taken on the line V—V of Fig. 3; Fig. 6 is a view taken on the line VI—VI of Fig. 4; Fig. 7 is a view taken on the line VII—VII of Fig. 6; Fig. 8 is a view, on an enlarged scale, taken on the line VIII—VIII of Fig. 2; Fig. 9 is a view taken on the line IX—IX of Fig. 8, and Fig. 10 is a sectional plan view of the structure of Fig. 9.

Briefly, the structure embodying my invention comprises a roll stand on which a pair of opposed rolls is pivotally supported for periodic oscillatory movements about parallel axes, in directions toward and away from each other. A blade or blank holder is supported for reciprocation in a rectilinear path to move the blades carried thereby forwardly between the rolls when they are in spaced-apart position, and to withdraw the blades,

the rolls being moved into engagement with the blades to effect a polishing operation thereon as they are being withdrawn from between the rolls. Each roll is provided with a driving motor.

Mechanisms are provided for oscillating the rolls and for reciprocating the blade holder in synchronism, and after the blades have been subjected to a predetermined number of polishing strokes, an automatic stopping device is actuated to stop the operation of the machine, thereby assuring proper polishing of the blades. The length of stroke of the blade-reciprocating mechanism is, of course, adjusted to permit polishing of blades of various lengths. Provision is also made for adjusting the polishing pressure of the rolls.

Simultaneously with reciprocation of the blade holder toward and away from the rolls, motion is imparted to the holder to move it in directions longitudinally of the rolls with a vibratile-reciprocatory motion derived from a hypocyclic crank movement, whereby the points of engagement between the rolls and the blades are constantly changing at a variable rate of speed in directions longitudinally of the rolls, and thereby a more uniform polishing action is effected regardless of irregularities and unevenness of the roll surfaces.

Referring now more particularly to Figs. 1, 2, 3 and 8, the machine comprises a base 10 on which is mounted a roll stand comprising a pair of uprights 11. The uprights carry cross-bars 13 and 14 which are journaled in the uprights at 15 and 16 respectively, for rocking movement about their respective axes. The rods 13 and 14 respectively carry brackets 17 and 18, which are rigidly secured to their respective rods. The bracket 17 is connected to its associated rod or cross-bar 13 by means of a pair of bearing bosses 20 and a boss 21, which are formed on the bracket 17, and through which bosses the rod 13 extends. Each of the bosses 20 and 21 is provided with a set-screw or a keying device which will hold the bracket 17 against movement relative to the rod 13, so that the bracket and the rod can be oscillated in unison about the axis of the rod in a manner to be hereinafter described. The lower bracket 18 is similarly connected to its associated rod 14.

A bracket 22 is connected to the bracket 17 at 50 one point by means of a pivot bolt 23, which has threaded connection with the bracket 17, as shown more clearly in Figs. 2 and 8. The bolt 23 extends through the midpoint of the bracket 22, so that the bracket 22 will have pivotal adjust- 55

ment on the bolt. The bracket 22 is adjustably connected to the bracket 17 by stud bolts 24, 25 and 26, which have threaded connection with the bracket 22, and whose shanks extend through 5 slots in the bracket 17, as shown more clearly in Fig. 1, so that the bracket 22 can be set in various angular positions with respect to the bracket 17.

The bracket 22 has forwardly projecting journals 30 in which are supported the ends of a shaft 31, which carries a polishing roll 32. The roll may be faced with any desired abrasive or polishing material such as emery, polishing rouge etc., and is here shown as built up of a series of 10 fabric discs which are assembled on the shaft and held thereon by clamping discs 34, which may be held in snugly assembled relation by means of clamping nuts and collars, such as indicated at 35 and 36, that are carried by the shaft 31. 15 The fabric discs are, of course, yieldable, and other material such as rubber could be substituted therefor if desired. For initial grinding and polishing, the discs may have peripheral faces or edges of emery, or be impregnated with emery 20 or the like. The roll shaft 31 is driven from an electric motor 38 that is bolted to the bracket 22.

The bracket 17 has a yoke-like extension carrying adjusting screws 40 and 41 (Fig. 1), whose ends engage a boss 42, projecting rearwardly from 30 the bracket 22. With the screws 24, 25 and 26 loosened, the screws 40 and 41 can be turned to effect adjustments of the bracket and the roll 32 carried thereby, relative to the bracket 17, about the pivot bolt 23 as an axis. The brackets 35 can be tightly secured in any such adjusted position by then tightening the bolts 24, 25 and 26. The roll 32 is thereby adjusted relative to a co-operating roll 44 which will be of similar construction to the roll 32.

40 The roll 44 is mounted upon a shaft 45, that is journaled in extensions 46 of a bracket 47 which is of a form similar to the bracket 22 and is connected to its bracket 18 by a pivot bolt 48. The bracket 47 is adjustable on the bracket 18 by stud bolts 50, 51 and 52 and screws 53 and 54 which 45 respectively correspond in function and operation to the members 24, 25, 26, 40 and 41. The roll shaft 45 is driven by an electric motor 37 that is mounted on the bracket 47.

50 It will be understood that knife blades, or other articles to be ground or polished, will pass between the rolls 32 and 44, and that in order to effect proper and uniform polishing action, the rolls must be properly spaced apart and be angularly adjustable relative to one another, in order 55 to compensate for unevenness in wear at various points throughout their lengths. It is for this reason that the adjustments above referred to are provided.

60 The rolls are supported by links or rods for vertical movement relative to one another whereby they can be separated to permit the insertion of blades or other articles to be ground or polished, and then brought into operative relation 65 with said blades to effect a polishing operation thereon while the blades are being drawn from the rolls. The rolls are driven in such direction that they exert a drag on the articles as they are being withdrawn from the pass of the rolls, during 70 the polishing action. In other words, during the polishing operation, the roll surfaces in contact with the blades are moved in a direction opposite to that in which the blades are being moved.

75 A vertically movable push rod or link 55 is piv-

otally connected at its upper end to an arm 56 that is rigidly secured to the journal extension 30 of the bracket 22, so that when the rod 55 is raised and lowered, the bracket 17, together with its associated bracket 22 and roll 32, is oscillated 5 about the axis of the bar 13. The bracket 17 has pivotal connection with one end of a link 60, whose other end is pivotally connected to a lever 61 that is pivotally mounted at 62 to the upright 10 11 (Figs. 2, 3 and 8). The lower end of the lever 61 is pivotally connected to a link 63 which has pivotal connection also with the bracket 18. It will be seen that by reason of the link connections referred to, the weight of the bracket 18 and the parts carried thereby, which tends to 15 cause them to move downwardly, will be counterbalanced by the weight of the upper bracket 17 and the parts it supports, and that when the upper roll is moved to a given vertical position, the lower roll will be correspondingly shifted in 20 the opposite direction.

The lower end of the push and pull rod 55 is pivotally connected to a lever 65 whose one end is pivotally connected to the frame 11 at 66. A yoke 67 loosely fits over the forward end of the 25 lever 65 and is yieldably urged toward the base by a spring 68. An adjusting screw 69 is provided in the yoke 67 and bears against the upper edge of the lever 65, so that the spring tension on the lever can be varied. The tension exerted by the 30 spring 68 yieldably urges the rolls toward one another and determines the polishing pressure exerted by the rolls.

The work-supporting and feeding mechanism includes a casing 70 which has a flanged base that 35 is slidably adjustable in slideways formed in the base 10, as shown more clearly in Figs. 1, 3 and 5. Adjustment of the casing 70 on the base 10 is effected by a screw 71. This adjustment is provided in order to position the casing 70 relative 40 to the rolls to permit of polishing blades of various lengths.

The casing 70 supports a motor 72, which is provided with a shaft that carries a pinion 73 (Fig. 4). The pinion drives a gear wheel 74, that 45 is mounted on a shaft 75 that is journaled in bearing brackets 76 (Figs. 4 and 5). The shaft 75 carries a worm 77 which meshes with a worm wheel 78. The worm wheel 78 is bolted to a supporting plate 79 that is formed integrally with 50 one end of a shaft 80, the shaft 80 being journaled in a bearing sleeve 81 that is carried by the casing 70.

A second plate or disc 79a is secured to the plate 79 in back-to-back relation thereto, and on 55 its inner face is provided with a bearing boss 82 for supporting the shaft 83 of a bevel gear 84. The other end of the shaft 83 is threaded for engagement with a crank member 85 that carries a crank pin 86. The member 85 is slidably 60 adjustable by the screw shaft 83 in guide wings or bosses 87, that are formed on the face of the disc 79a.

Rotative adjustment of the crank pin 86 radially of the worm gear 78 is effected by a bevel 65 pinion 88 that meshes with the gear 84. The pinion 88 is mounted on a shaft 89 that extends centrally through the shaft 80. The shaft 89 is squared at its outer end for the reception of a wrench or handle. It will be seen that the shaft 70 80, shaft 89, bracket 82 and crank pin member 85 rotate as a unit with the worm wheel 78. The adjustment of the shaft 83 is for the purpose of varying the "throw" of the crank pin 86, since its radius of movement, and therefore the length of 75

throw, will vary with its distance from the axis of the worm wheel 78.

The crank pin 86 carries a slide block 80 which is disposed within a slot 81 in a lever 92, the lever 92 being pivotally mounted on a shaft 93 that is journalled in bosses projecting upwardly from the bottom of the casing. The upper end of the lever 92, as shown more clearly in Figs. 4 and 6, has pivotal connection with a link 94, that is in turn connected to a rack bar 95. The rack bar 95 is positioned between guide plates 96 which are carried by the casing 70, and is provided with teeth on its opposite faces that are in mesh with segmental gear members 97 and 98, respectively.

10 The gear members 97 and 98 are mounted on vertical shafts 99 and 100, respectively, that are journalled in the casing 70. The upper ends of the shafts are connected to cranks 101 and 102, respectively, which in turn are respectively connected to links 103 and 104. The links 103 and 104 at their free ends are journalled on a stub shaft 105 (Figs. 8 and 9), which is carried by an anti-friction roll cage 106. The roll cage 106, as shown more clearly in Figs. 8, 9 and 10, consists of a top plate having downwardly extending marginal flanges forming an inverted box which encloses a plate member 180 of a carriage 107. Anti-friction rollers 181 that are held in assembled relation within a roller cage 182 are interposed between the top of the plate member 180 and the under side of the upper plate portion of the roll cage 106. A neck portion 183 connects the supporting plate 180 with the frame of the carriage 107 and extends through an elongate slot 184, formed in a sectional bottom plate 185 that is secured to the marginal flanges of the cage 106. Anti-friction rollers 186 and 187 are disposed at opposite sides of the neck 183 in position between the bottom plate 185 and the under side of the 20 plate member 180. The carriage 107 is thus supported in suspension by the roll cage 106 at the ends of the arms 103 and 104.

25 The carriage 107 is provided with grooved wheels 108 that engage a track bar 109. The bar 45 109 is, at its ends, mounted upon arms 110 of a rock shaft 111, that is journalled in the housing 70. It will thus be seen that by oscillating the shaft 111, the bar 109 will be moved in directions indicated by the arrows in Fig. 5 and move the 50 carriage 107 relative to the roll cage 106 in directions parallel to the axes of the rolls 32 and 44. This movement of the carriage is effected independently of its movement toward and away from the rolls, for a purpose to be hereinafter described.

55 The carriage member 107 has a bracket 115, which carries a work holder. The ends of the bracket 115 (Figs. 8, 9 and 10) have threaded bosses for the reception of adjusting screws 116. The upper ends of the screws 116 are rotatably 60 connected with a supporting plate 117. The work holder comprises a pair of hinged plates 118 which are hingedly connected and which are adapted to grasp or clamp blades or other work pieces 119. A pair of threaded eyebolts 120 have 65 swivel connection with the lower plate 118 and are movable into slots in the edge of the upper plate, whereupon nuts 121 can be employed to clamp the plates together, then firmly hold the work pieces 119. The blanks or work pieces 119 are preferably 70 formed with notches in the edges of their shanks, as shown more clearly in Fig. 10, for engagement with studs 122 on the lower plate 118, whereby an interlocking effect is had, which prevents pulling the blades out of the holder under the frictional 75 drag of the polishing rolls. Angle clips 123 car-

ried by the lower plate 118 serve to detachably secure the work holder 118 to the supporting plate 117.

The arms 101 and 102 at their upper ends carry bearing housings 124 and 125 respectively, for the 5 shafts on which the links 103 and 104 are mounted (Figs. 1, 2, 3 and 8). At their lower ends, the arms 101 and 102 are supported on the shafts 99 and 100, above referred to, which are in turn supported in the casing 70. The supporting shafts 10 at the points of pivotal connection of the arms 101 and 102 and the links 103 and 104 are effective to prevent horizontal deflection or sagging of the arms and the work holder.

Oscillation of the rock shaft 111 and the guide track 109 to reciprocate the work holder and the knife blades longitudinally of the rolls, while in the roll pass, is effected by a crank or lever arm 126 (Fig. 5) which is rigidly secured to the rock shaft 111. A link or connecting rod 127 is pivotally connected to the outer end of the lever arm 126, and at its lower end is connected to a crank or an extension 128 of a crank shaft 129 (Figs. 5 and 6). The shaft 129 is journalled in a rotating barrel or cage 130 which in turn is formed on the end of a shaft 131, that is journalled on a supporting plate 132 which is detachably bolted to the end of the casing 70.

The plate 132 has a cylindrical projection 133 within which is formed a bearing surface for supporting the barrel 130. An internal gear 134 is mounted within the extension 133 and meshes with a gear wheel 135 that is secured to the shaft 129. The shaft 129 is journalled eccentrically of the shaft 131, so that when the shaft 131 is driven, as hereinafter explained, the gear wheel 134 will cause rotation of the gear wheel 135, during rotation of the shaft 131, whereby the crank 129 will be rotated on its own axis during movement thereof in a path concentric to the axis of the 40 barrel 130 and the shaft 131, thereby producing a hypocycloidal motion which, through the connecting rod 127 and the rock shaft 111, will be transmitted to the track 109, and produce a vibratory and reciprocating movement of said 45 track 109 and the work holder, in directions longitudinally of the polishing rolls.

This combination of short vibratory movements with the longer reciprocating movements, in directions longitudinally of the rolls, results in a 50 better and more uniform polishing of knife blades and the like, than would be possible with simple reciprocatory movements, thereby avoiding a tendency toward zones of very high polish and contrasting zones which are less brightly polished, 55 or in other words, eliminating streakiness of polishing which is frequently present when the blades are simply reciprocated longitudinally of the rolls while being moved into and out of the roll pass.

The shaft 131 carries a bevel gear 137 which is driven from a bevel pinion 138 that is secured to a shaft 139. The shaft 139 is journalled in bearing bosses upon the supporting plate 132. A pinion 140 is secured to the shaft 139 and is driven by 65 a gear wheel 141, that is bolted to the supporting plate 79, which as heretofore explained, has connection with the worm wheel 78.

Another important feature of my construction resides in the fact that adjustment of the 70 throw of the crank 85, as heretofore referred to, which moves the work into and out of the roll pass, can be made to suit various lengths of knife blades or the like, in order to effect proper polishing thereof, but such adjustment will not affect 75

the vibratory and reciprocatory movements above referred to. In other words, shortening of the feed stroke into and from the roll pass will not reduce the amplitude of vibratory movements in 5 directions longitudinally of the rolls, so that the efficacy of the cross-polishing action remains the same regardless of the length of feed stroke employed.

The actuation of the lever 65 to effect movement of the polishing rolls 32 and 44 toward and from one another, is effected by the worm wheel 78 which carries a roller 148 (Figs. 1 to 6), which, during rotation of the wheel, periodically engages a camming extension 149 of a crank 150, which 10 is secured to a shaft 151, that is journaled in the casing 70. At its outer end, the shaft 151 carries a lever arm 152 which in turn carries a push pin 153 that engages a groove in the under 15 side of the lever 65. It will be seen that as the 20 rock shaft 151 is oscillated during rotation of the worm wheel 78, the lever 65 will be periodically raised to effect separation of the polishing rolls.

This separating movement of the rolls occurs 25 just when the blanks are being advanced into the roll pass, or between the rolls, through forward movement of the carriage 107, as heretofore described. When the carriage is fully advanced, the lever 65 will be permitted to descend 30 and bring the polishing rolls into engagement with the knife blades or other work pieces at points adjacent to where they are clamped by the work holder. Thereupon, with the rolls rotating, the carriage is retracted in a direction to 35 draw the work from the roll pass, and the vibratory movements in directions longitudinally of the rolls, as heretofore described, are simultaneously effected.

A guard or shield 155 is provided for preventing 40 the operator getting his hands caught between the rolls (Figs. 3 and 8). The shield is mounted upon a rock shaft 156 that is journaled in the bearing bosses 30. A crank arm 157 is secured to the rock shaft and has connection with a link 158 whose lower end is connected to a lever 159 that is pivotally mounted at 160 to the side of the casing 70. The lever 159 carries a cam roller 161 that has cooperative engagement with a cam disc 162 which is mounted on the shaft 80. The shield 155 will therefore be periodically raised 45 and lowered during the operation of the mechanism. The timing or adjustment is such that the shield will be in its lower or protective position when the carriage 107 is retracted, and will be raised automatically while the carriage is being advanced toward the roll pass.

A complete polishing or abrading operation 50 ordinarily consists of repeatedly moving the work holder toward and away from the roll pass while oscillating the holder, as above described. For example, the work holder may be advanced and retracted five times. The number of times which the work holder is reciprocated toward and from the pass of the rolls, is variably and automatically controlled by mechanism which includes a rack bar 165 which is slidably supported in a bracket 166 which is secured to the casing 70. The rack bar carries a push rod 167 which is engageable with a rocking lever 170 when the rack bar is advanced to a predetermined point. The lever 170 is pivotally mounted on the side of the casing 70 and engages the push button of a switch 171 to break the circuit of the driving motor 72.

The rack bar is actuated by a pinion 173 which 75 is journaled in the bracket 166. Step-by-step

movement is imparted to the pinion 173 to advance the rack bar, by the cam 162 which carries a pin 174 which, during each rotation of the cam, will engage one of the teeth of the pinion 173 and impart slight rotative movement there- 5 to. The cam 162 will make one complete rotation for each cycle of reciprocation of the work holder toward and from the roll pass. At certain adjustments of the rack bar and push rod, the cam 162 may rotate perhaps five times before 10 the rack bar is advanced far enough to actuate the lever 170 that breaks the motor circuit.

After the motor circuit has been broken, as above described, the rack bar and its rod 167 will be manually pushed back away from the lever 170. Scale markings can be placed on the rod 167, so that it can readily be pushed back such distance that a desired number of rotative movements will be imparted to the pinion 173 before the motor circuit is broken. The retractive 20 movement and adjustment of the rack bar, of course, turn the pinion 173 backwardly, the pinion being at that time out of engagement with the pin 174, and hence free to rotate.

The automatic stop mechanism eliminates too 25 many strokes on abrasive operation, thereby protecting against wearing the material too thin, and, also, assures that for finishing operations the work will be given a sufficient number of strokes to obtain uniformity of polishing. 30

A cycle of operations is initiated when the vertical push rod 55 is in its upper position and the polishing rolls 32 and 44 therefore separated, with blanks 119 secured in the work holder, the driving motors for the rolls 32 and 44 being normally constantly driven. The motor 72 is started, whereupon the work holder will be advanced to move the blanks between the rolls, this movement being effected by the crank 85 which, through the lever 92, rack bar 95, cranks 101 and 40 102, and links 103 and 104, moves the work holder toward and from the roll pass. When the blanks have been entered between the rolls, the cam roller 148 will pass off the extension 149 of the crank shaft 151, thus releasing the rod 45 and allowing the lifting lever 65 to descend, and the rolls 32 and 44 to move against the blanks. The crank 85 will then have reached the point at which it effects movement of the work holder away from the rolls, during which movement the 50 blanks are polished.

During this retractive movement of the work holder, it is reciprocated in directions longitudinally of the rolls, by the barrel 130 which functions as a crank and acts through the crank 128, the link 127, the crank arm 126, rock shaft 111, bar 109, and guide wheels 108, to reciprocate the holder. The work holder carriage is simultaneously oscillated or vibrated during its movement longitudinally of the rolls, within the path of 60 such movement. This oscillation is effected by the hypocycloidal motion produced by the crank shaft 128 whose pinion 135 engages the stationary ring gear 134, so that there is a turning of the crank 128 upon the crank member 130, both 65 acting upon the link 127.

These operations are automatically repeated until the motor 72 is stopped. Stopping of the motor is effected automatically by the rack bar 165 engaging the switch-operating lever 170. 70 The rack bar is moved outwardly toward the switch lever a predetermined distance during each cycle of movement by the work holder toward and from the roll pass.

I claim as my invention:

1. Polishing apparatus comprising a polishing roll, a work holder, driving mechanism for recurrently moving said work holder toward and from the polishing roll to move a work piece on the face of the roll, a control device movable into position to interrupt the operation of said driving mechanism, means operable during movement of the driving mechanism for intermittently advancing said control device toward the said interrupting position, and means for adjusting the distance of movement required for said control device to become operative. 5
2. Polishing apparatus comprising a polishing roll, a work holder, driving mechanism for recurrently moving said work holder toward and from the polishing roll to move a work piece on the face of the roll, a control device movable into position to interrupt the operation of said driving mechanism, means operable during each cycle of movement of the work holder for advancing the control device one step toward the said interrupting position, and means for adjusting the distance of movement required for said control device to become operative. 10
3. Polishing apparatus comprising a supporting means, a pair of brackets each pivotally mounted on said supporting means, a polishing roll journaled in each of said brackets, the rolls being mounted in vertically spaced cooperative relation, counter-balancing link connections between said brackets so arranged that the gravitational force imposed upon each bracket is transmitted as a lifting force to the other bracket, a work holder, mechanism for moving the work holder toward and from the rolls, and means operated in timed relation to the movement of the work holder for raising and lowering one of said brackets. 15
4. Polishing apparatus comprising a supporting means, a pair of brackets each pivotally mounted on said supporting means, a polishing roll journaled in each of said brackets, link connections between said brackets so arranged that pivotal movement of one of the brackets will effect movement of the other bracket in the opposite direction, a work holder, mechanism for moving said work holder toward and from the rolls, and means operated in timed relation to said mechanism for oscillating one of said brackets on its pivot. 20
5. Polishing apparatus comprising a pair of rolls arranged in cooperative relation and with their axes normally in approximate parallelism, a bracket having bearings for one of said rolls, a support for the bracket, means for tiltably adjusting said bracket on its support, to vary the relative angularity of the rolls, means for moving the rolls toward and away from one another, a work holder, and means for moving the work holder toward and from the roll pass in timed relation to said movement of the rolls. 25
6. Polishing apparatus comprising a polishing roll, a work holder, means for moving the work holder toward the roll, in a plane generally tangential thereto, means operating in predetermined relation to said movement of the work holder, for moving the roll in directions perpendicular to said plane, to move it out of the path of work carried by the holder and to then move the roll against the work, means for withdrawing the work holder from the roll, and means for simultaneously imparting combined reciprocatory and shorter vibratory movements to the holder in directions longitudinally of the roll. 30
7. Polishing apparatus comprising a polishing roll, a work holder, means for moving the work holder toward and from the polishing roll to move a work piece on the face of the roll, and a device operable simultaneously with said means, for effecting combined reciprocatory and shorter vibratory movements of the work holder in directions transversely of the path of movement of the work holder. 35
8. Polishing apparatus comprising a pair of cooperatively-mounted polishing rolls, a pivotally-mounted bracket for each of said rolls, movable toward and from one another, counter-balancing link connections between said brackets, so arranged that movement of either bracket in one direction will cause movement of the other bracket in the opposite direction, a work holder movable to carry a work piece into and from the roll pass, and means operating in synchronism with movement of the work holder toward the roll pass to effect separating movement of the said brackets. 40

ALFRED E. HAMILTON.
